UNITED STATES PATENT OFFICE

2,055,190

APPARATUS FOR THE MANUFACTURE OF
COMBUSTIBLE GAS

Daniel J. Young, Tacoma, Wash., assignor to
Young-Whitwell Gas Process Company, Ta-
coma, Wash., a corporation of Washington

Original application August 13, 1928, Serial No.
299,380, which in turn is a division of Serial No.
183,625, April 13, 1927. Divided and this ap-
plication March 31, 1931, Serial No. 526,703

4 Claims. (CL 48—71)

The invention relates to a new and useful apparatus for the manufacture of motor fuel and similar products. The present application is a division of my application Serial No. 299,380, filed 5 August 13, 1928, which in turn is a division of an earlier application Serial No. 183,625, filed April 13, 1927, now Patent No. 1,706,686, granted March 26, 1929.

In the manufacture of carbureted water gas, 10 it is well known that there has always been produced a certain amount of by-product commonly called water gas tar. There are also contained in water gas certain unsaturated hydrocarbons which may be condensed or otherwise extracted 15 from the gas in a known manner. I have discovered that the quality and amount of these tars and unsaturated hydrocarbons can be to a large extent controlled if means are provided for a control of temperature and other conditions in 20 the various parts of an oil-treating apparatus similar to a water gas set. I have also discovered that the addition of various gases and liquids into such an apparatus under controlled conditions of temperature will materially affect the production 25 of the tars and hydrocarbons.

The principal object of my invention is ac- 30 cordingly to provide an apparatus similar to a water gas set, so designed that the temperature and other conditions in the various parts of the apparatus may be easily and readily controlled. It is well known that in the heating of a water 35 gas set, when air is blown through the fuel bed, a producer gas is formed, and that the location of the secondary air to burn this producer gas governs the point of maximum temperatures in the checkerbrick.

A standard water gas set is generally considered 40 to include a generator or fuel chamber, and heat interchanger or interchangers commonly known as the carburetor and superheater. The accepted form of water gas set commonly known as a three-shell set was adopted for structural and oper- 45 ating advantages. Similar results may be ob- tained in a two or four shell set, but the economic reasons of ease of operation, cost of original con- struction, ease of repair and maintenance, cost 50 of necessary superstructures such as buildings and fuel handling equipment, inconvenience of auxiliary apparatus and many factors have proven the three-shell set to be, ordinarily, the most economical and efficient. I will describe an apparatus similar to the three-shell set, as a pre- ferred design.

The present invention is directed primarily to 55 an apparatus especially adapted for flexible con-

trol to produce proper temperature and other conditions for the various reactions to best take place and is not concerned specifically with methods of handling the products, either gaseous or liquid, after having been discharged from the set. 5

The invention may be more readily understood by reference to the accompanying drawings, which are intended for the purpose of illustration only, and are largely diagrammatic in character.

In the drawings,

Fig. 1 is a diagrammatic view showing an ar- 10 rangement of the gas making and oil treating portion of the apparatus, including the scrubber, or condenser, in which liquid and gaseous products are separated, no portion of the cracking or purifying apparatus for treating the liquids after 15 separation being shown, as any well-known or standard apparatus may be employed for this purpose;

Fig. 2 is a vertical section showing a gas gen- 20 erator and two heat interchangers, and the con- nections for supplying steam, air, gas and fuel, and for withdrawing gas from the set, this con- struction being slightly different from the ar- 25 rangement shown in Fig. 1, in that in Fig. 1 all the connections for supplying air, gas or the like are interconnected, and all the gas outlets 30 are interconnected, whereas in Fig. 2 the air and gas inlets are separate and distinct and the various gas offtakes are also separate from each other;

Fig. 3 is a more detailed top view of the ar- 35 rangement shown diagrammatically in Fig. 1; Fig. 4 is a bottom sectional view similar to Fig. 3, but showing the lower connections; and

Fig. 5 is a view showing the relief holder and scrubber, including the outlet from the scrubber by which gas may be conveyed to a storage holder and liquids conveyed to suitable sepa- 40 rators or stills.

The present apparatus has as the basis of its design the standard water gas set, to which is added means for securing added flexibility of operation, so that in its preferred form the im- 45 proved apparatus includes means for selectively introducing air or other gases, steam, powdered fuel, oil or other liquids or fuels, and means for selectively withdrawing gas or other products at each of the following points:

1st.—Bottom of generator	50
2nd.—Top of generator	
3rd.—Top of carburetor	
4th.—Bottom of carburetor	
5th.—Bottom of superheater	
6th.—Top of superheater.	55

These specific locations are selected largely for structural and operating reasons. The object of these many connections is to provide both an inlet for the various necessary elements employed in the process, and an outlet for the resultant products at every point where material differences in temperature and other conditions may be expected, and the points selected practically cover all such points. Valves or other means of controlling such inlets and outlets are provided so that the direction of flow through the set may be controlled as desired. For instance, the flow may be from the bottom of the generator through the carburetor and superheater, leaving the set at the top of the superheater, or it may be just the reverse of this. The flow may be from the bottom of the generator and from the top of the generator, leaving the set at the bottom of the carburetor. It may also be desirable to have connections similar to the old up and down run water gas set so as to make the flow even more flexible, although it is believed that such connections necessitating expensive and inefficient valves for handling hot gases will not be necessary.

In other words, my invention consists in providing flexible means for producing the widest possible variety of conditions of temperature and raw product control in a simplified or modified standard apparatus.

The apparatus includes as a basis of its design the usual water gas set, with certain modifications to be described hereinafter, and comprises the generator or fuel chamber 1, and the heat interchangers 2 and 3, commonly known as the carburetor and superheater respectively.

These shells are of substantially standard design, and as they are well known in the art, they need not be described in detail, except with reference to the various connections by means of which the control of temperature and other conditions is obtained. The generator may be supplied with the charging means 80, Fig. 2, described in my Patent, No. 1,468,190, and the superheater 3 may be provided with a blast cap 32 as shown. The carburetor and superheater may be provided respectively with checkerbrick 23 and 33 of any desired description. A wash box 13, relief holder 14, scrubber 15, storage holder 16 and recirculation pump 17 may be provided, these being of any desired or standard construction.

From the bottom of the scrubber a liquid overflow pipe 27 leads to the various devices for purifying, separating, cracking and otherwise treating the liquid constituents derived from the process, such products including tar, ammonia, and many other important constituents. From these constituents I am enabled to separate out a product which may be used successfully as a motor fuel. The specific apparatus for cracking, purifying and otherwise treating the said liquid constituents is not shown in detail, as well-known apparatus may be employed for this purpose in connection with the other apparatus herein described.

The connections for supplying air, steam, gas, fuel, oil and the like to the generator, carburetor and superheater, and for withdrawing gas and oil vapors from the top and bottom of the generator, carburetor and superheater will now be described.

For simplicity, all gas or air inlets and their respective valves are referred to by the letter A with suitable differentiating exponents; all gas

outlets and their valves are designated by the letter B with suitable exponents; all steam and water inlets and their control valves by the letter C with suitable exponents, and all oil or atomized fuel pipes, inlet or control valves are designated by the letter D with suitable exponents. Valves which control the flow through the set as a whole, rather than particular inlets or outlets are designated by the letters E, F, G and H in Fig. 2. In Figs. 1, 3 and 4, which show the various air supply pipes interconnected, and the various gas offtakes interconnected, additional control valves as I, I', J, J', K, K', L and L' are required.

The connections to and from the three main shells of the set, namely the generator, carburetor and superheater, will be most readily understood by reference to Fig. 2, for the reason that in this figure no attempt is made to show interconnections between the various air inlets, and between the various gas offtakes. In practice it is frequently desirable to have the various gas offtakes entirely separate, for the reason that constituents of widely varying qualities can be taken off from the individual offtakes and used for various purposes. Where, however, all the gaseous constituents are to be mixed in a single holder, the arrangement shown in Figs. 1, 3 and 4 may be employed.

Referring particularly to Fig. 2, the air or gas inlet control valves are designated as A', A², A³ and A⁴. The gas offtake control valves are shown at B', B², B³ and B⁴. The steam or water inlet control valves are designated as C', at the bottom of the generator, C² at the top of the generator, C³ at the top of the carburetor, C⁴ at the bottom of the carburetor, C⁵ at the bottom of the superheater, and C⁶ at the top of the superheater. The oil or atomized fuel, which may be either liquid or finely divided solid fuel, may be supplied through control valves D' at the bottom of the generator, D² at the top of the generator, D³ at the top of the carburetor, D⁴ at the bottom of the carburetor, D⁵ at the bottom of the superheater, and D⁶ at the top of the superheater.

It will be noted that a permanently free and unobstructed passageway may be had for the passage of gas through the system as a whole through pipe connection 4 connecting the top of the generator with the top of the carburetor, and through pipe 43 connecting the bottom of the carburetor with the bottom of the superheater.

Control valves E and F are located at the passage 41 connecting the bottom of the generator with the bottom of the carburetor, and control valves G and H are located in the passage 31 intermediate the tops of the carburetor and superheater.

The air supplied through the various inlets may come from separate and independent sources, if desired, and likewise the products taken off from the various gas offtakes may go to separate wash boxes, purifiers, separators, and other known apparatus for treating combustible gas, and its by-products, both liquid and gaseous.

If desired, however, the air inlets may be interconnected, and likewise the gas offtakes may be interconnected, as shown in Figs. 1, 3 and 4, all the gases passing from a single common off-take pipe to wash box 13, through pipe 21 to relief holder 14, thence through pipe 22 to the scrubber 15, containing trays 24 in which the liquid and gaseous constituents are roughly separated, as by means of the water, tar or other

liquid spray 25 at the top of the scrubber, the gases passing through pipe 26 to the relief or storage holder 16, and the liquid constituents passing through pipe 27 to the separators, stills and other apparatus for further treatment, in a well-known manner.

Where it is desired to recirculate a portion of the combustible gases taken off from the set in the manner set forth in Whitwell Patent No. 10 1,752,223 granted March 25, 1930, pipe 28 connects with pump or fan 17, the said pipe being supplied with a control valve 29. Thus, when the valve 29 is open and the pump 17 in operation, a portion of the gases is by-passed through pipe 15 30 to the air main A which supplies all the air inlets.

If desired, a steam or other jet device placed in the by-pass connection may be employed for effecting the recirculation of gas, in place of the 20 pump or fan 17.

Air may be supplied to the upright main A through pipe a controlled by a valve a'. Likewise valves a² and a³ are provided in the main A above and below the pipes a and 30. The air main A 25 connects two sets of pipe connections, one at the top and one at the bottom of the set, through which the air or gas, or a mixture of both, may be supplied to the shells 1, 2 and 3, through the inlets previously described. The upper pipes are 30 controlled by valves I, J, K, and L, while the lower pipes are controlled by similar valves I', J', K', and L'.

Similar sets of pipes connect the gas offtakes at the top and bottom of the system, the upper 35 set being controlled by valves B² and B³, while the lower set is controlled by valves B' and B'. An upright gas main B connects the upper and lower sets of pipes, and from the bottom of this main the gas offtake 20 leads to the wash box 13, as 40 previously described.

The parts and connections described above in detail are to be understood as illustrative only, as showing one method for carrying out the processes described herein, but it will be understood 45 that other means may be employed for carrying out the same or equivalent processes.

I will describe several cycles of operation, all of which will produce a considerable amount of motor fuel and other liquid products, and at the 50 same time as a by-product produce combustible gas which may be used in an industrial or commercial gas plant.

1. (a) Blast—preferably with air, as in the standard water gas operation, but add the secondary air at the bottom of the superheater. This 55 will heat the superheater somewhat more than in the standard water gas operation, and the carburetor somewhat less. Referring to Fig. 2, this operation may be accomplished by opening valves A' and A⁴, E and the stack valve, all the other valves shown in this figure being closed.

(b) Run—during the run I introduce steam at the bottom of the generator, oil at the top of the carburetor, and if desired, at the top of the 65 superheater, taking off gas at the bottom of the superheater. The oil introduced into the superheater is vaporized and mingle with the carbureted water gas from the carburetor, further enriching such gas. The temperatures within 70 the generator carburetor and superheater may be varied according to the type of product desired.

After such a cycle, I introduce steam at the 75 top of the superheater and take off gas at the bottom of the generator, to make water gas, and

to remove the carbon which has accumulated on the checkerbrick. It is obvious that the resultant gas will contain a much larger amount of liquids than standard water gas, which liquids may be recovered by any of the well-known methods. 5

It is not necessary to introduce oil at both the carburetor and superheater, as may be introduced at either point, or at the top of the generator, or at all three locations at once. Pulverized solid fuel containing volatiles may be substituted for 10 the oil, if desired.

The first part of cycle 1b may be accomplished by leaving valves C', D³, D⁴ and B' open, all the other valves shown in Fig. 2 being closed.

The second part of cycle 1b may be performed 15 by leaving valves C⁴, E and B' open, all the others shown in Fig. 2 being closed.

2. (a) Blast—preferably with air, according to the standard water gas method. (b) Then introduce oil at the top of the superheater and take 20 out the resulting combustible gases and vapors at the bottom of the generator. The gaseous product issuing from the bottom of the generator includes both condensable and non-condensable gases, produced (1) by the vaporization of the oil or other hydrocarbon, (2) by distillation of the fuel within the fuel bed of the generator, and (3) by the reaction between the highly heated oil gases or vapors and the carbonaceous material 25 within the fuel bed of the generator. The quality of the product varies according to temperatures and pressures existing at different parts of the set, and according to the quantity of enriching material employed. (c) Follow this with a back steam run to remove the carbon. Such operation will deposit on the fuel bed acting as a filter most of the heavier tars, thus tending to build up the fuel bed, and the resultant gas will contain only the lighter condensable hydrocarbons, which may be recovered. This method of 30 operation will be desirable when oils of high free carbon content are used.

During cycle 2a, the valves A', E, A² and the stack valve are open, and all the others are closed. During 2b the valves D⁴, E and B' are open and 45 the others closed. During 2c the valves C⁴, E and B' are open, and the others closed.

The gas and volatiles are withdrawn from the bottom of the generator.

In this cycle also, the oil may be admitted at 50 the carburetor, or at the top of the generator, or at two or more locations at once, if desired, and, as heretofore stated, pulverized solid fuel containing volatiles may be substituted for the oil.

3. (a)—Air blast in the standard manner and 55 then (b) introduce oil at the top of the carburetor, if desired, and at the top of the superheater, taking off gas at the bottom of the superheater, using no steam during this part of the run. At the end of the oil run steam may be used, employing either an up-run or a back-run to free the superheater of carbon. When the set is operated in the manner above described, the principal function of the fuel bed in the generator is to supply the necessary heat during the blasting step to raise the temperature of the checkerwork in the carburetor and superheater sufficiently high to efficiently vaporize or crack the hydrocarbon introduced during the subsequent oil run. The oil may be completely cracked to 60 provide a fixed gas, or if lower temperatures are employed, the oil is merely vaporized, and portions of the out-going product may be subsequently condensed to produce a liquid fuel having the desired characteristics. The principal 65

purpose of the steam back-run is to free the superheater of carbon, although water gas is produced by the reaction between the highly heated steam and the accumulated carbon on the checkerbrick. If desired, an air blast may follow the oil run and precede the back steam run, in order to maintain the temperature within the superheater at a sufficiently high level to insure the reaction between the steam and carbon. The air blast assists in the removal of carbon.

In 3a the valves A', E and A² and the stack valve of Fig. 2 are open, and the others closed. During the first part of 3b, in making an oil run, the valves C', H and B³ are open and the others closed. In making a steam back-run, the valves C⁶, E and B' of Fig. 2 are open and the others closed.

In order to separate the gases taken off from various outlets, it may be desirable to provide 20 separate means for withdrawing and storing gas from each outlet, and I therefore prefer to provide means for the separation of the gas from each outlet from the other gases. For instance, the gases made when no oil is being introduced 25 will be comparatively low in heating value, and may be used for heating stills, boilers or other accessories. The rich gas taken off during the oil run may be first stripped of its liquid contents and used for commercial purposes. Any 30 ammonia present may also be separated in a well-known manner.

The gases produced under different cycles will vary materially in specific gravity, and this fact may make it desirable to keep them separate.

35 The gas, after having the valuable oils removed, may be of such quality that it is not desirable to use it as such. With the apparatus described, this gas may be passed through the set again by any suitable means, as the pump 17, and 40 again subjected to heat, which will change it into the desired quality, such recirculation being described in the Patent No. 1,752,223 of George E. Whitwell, granted March 25, 1930.

It will be obvious that the present application 45 embodies the back-run principle specifically claimed in its relation to a gas-making process in other of my patents and applications. The apparatus employed is substantially the standard water gas apparatus, with modifications, which 50 may be readily applied, and is simple in construction and easy to operate, in such a manner that an indefinite variety of temperature conditions may be obtained whereby the quality and composition of the resulting product may be regulated 55 as desired. In addition, there is described an easy and efficient means for producing the heat employed in the gas-making and oil-cracking operations, making use of the ordinary standard water gas generator, this generator being utilized 60 for the water gas reactions when desirable. Also, simple means are provided for passing steam over the checkerbrick of the carburetor and superheater, thus freeing them from an accumulation 65 of carbon.

65 The raw products used are cheap and easily obtainable. For example, crude oil may be used in the carburetor and superheater in place of the expensive gas oils at present employed, or finely divided powdered fuel containing volatiles may 70 be employed in place of the oil. The gases employed are generally air and steam, though for the distilling operation hydrogen, or even an inert gas such as nitrogen, may be used in place of or together with steam during the back-run, 75 to serve as a carrier of heat, or as a source of

nitrogen, where ammonia is to be recovered from the product. Also, where oxygen is available, this may be substituted for the air used in blasting, under certain circumstances. Instead of steam, water may be employed. It will accordingly be understood that where the term "fluid" is used in the accompanying claims, it is intended to be given broad interpretation, as covering any or all of the above-mentioned products, as well as other gaseous or liquid media.

Obviously specific details of the apparatus may be varied within the scope of the appended claims.

What I claim is:

1. An apparatus for making combustible gas, 15 comprising a single generator adapted to contain a fuel bed therein, a single carburetor, a single superheater and a wash box, gas passages connecting the generator and carburetor and the carburetor and superheater respectively, combustible gas off-takes leading from both the top and bottom of the generator and from both the top and bottom of the superheater to the wash box; means for supplying primary air for blasting purposes to the generator; means for passing hydrocarbon fluid into and through the superheater, thence into and through the carburetor and into and through the fuel bed in the generator; means for withdrawing the resultant combustible gas from the generator and means for recirculating 30 a portion of the combustible gas thus withdrawn through the superheater, carburetor and generator.

2. An apparatus for making combustible gas, 35 comprising a single generator adapted to contain a fuel bed therein, a single carburetor, a single superheater and a wash box, gas passages connecting the generator and carburetor and the carburetor and superheater respectively, combustible gas off-takes leading from both the top and bottom of the generator and from both the top and bottom of the superheater to the wash box; means for supplying primary air for blasting purposes to the generator and means for supplying combustible gas making fluids to the generator, carburetor and superheater.

3. An apparatus for making combustible gas, 50 comprising a single generator adapted to contain a fuel bed therein, a single carburetor, a single superheater, gas passages connecting the generator and carburetor, and the carburetor and superheater respectively, combustible gas off-takes leading from both the top and bottom of the generator, from both the top and bottom of the carburetor and from both the top and bottom of the superheater, means for supplying primary air for blasting purposes to the generator and means for supplying combustible gas making fluids to the generator, carburetor and superheater.

4. An apparatus for making combustible gas, 60 comprising a single generator adapted to contain a fuel bed therein, a single carburetor, a single superheater and a wash box, gas passages connecting the generator and carburetor, and the carburetor and superheater respectively, combustible gas off-takes leading from both the top and bottom of the generator, from both the top and bottom of the carburetor and from both the top and bottom of the superheater to the wash box, means for supplying primary air for blasting purposes to the generator and means for supplying combustible gas making fluids to the generator, carburetor and superheater.
